J. NORRIS AND J. I. PEARSALL,
SHINGLE REBALING MACHINE,
APPLICATION FILED AUG. 26, 1918.

1,346,241.

Patented July 13, 1920.

UNITED STATES PATENT OFFICE.

JOHN NORRIS AND JESSE I. PEARSALL, OF MASON CITY, IOWA.

SHINGLE-REBALING MACHINE.

1,346,241.

Specification of Letters Patent. Patented July 13, 1920.

Application filed August 26, 1918. Serial No. 251,989.

To all whom it may concern:

Be it known that we, JOHN NORRIS and JESSE I. PEARSALL, citizens of the United States of America, and residents of Mason 5 City, Cerro Gordo county, Iowa, have invented a new and useful Shingle-Rebalining Machine, of which the following is a specification.

The object of this invention is to provide 10 improved means for baling objects such as shingles.

A further object of this invention is to provide improved means for re-balining shingles the bale of which has been accidentally 15 loosened or destroyed in handling or transportation.

A further object of this invention is to provide improved means for compressing laminated objects and holding the same in 20 compressed condition preliminary to the application of a bond or retaining element thereto.

Our invention consists in the construction, arrangement and combination of elements 25 hereinafter set forth, pointed out in our claims and illustrated by the accompanying drawing, in which—

Figure 1 is a plan of the complete device, the compressing lever being shown in closed 30 position and one member of the retaining element being shown in position for reception of objects such as shingles. Fig. 2 is a cross-section on the indicated line 2—2 of Fig. 1 illustrating the manner of collocating 35 and compressing in laminated form a quantity of objects such as shingles preliminary to application of a retaining element or bond thereto, portions of the retaining element or bond being shown in position for practical use. Fig. 3 is a detail cross-section on the indicated line 3—3 of Fig. 2.

In the construction of the device as shown a suitable base is constructed preferably in the form of a rectangular frame composed 45 of angle bars 10, 11 at the long sides and 12 at the ends or short sides, one of the latter being shown in Fig. 2, which bars are notched and overlap at their ends. The base frame is overlaid by transverse metal strips 13 preferably spaced apart and riveted at their ends to the side bars 10, 11. A back frame is composed of angle bars 14, 15 parallel with each other, vertically spaced apart, and connected by vertically arranged 50 metal strips 16 riveted at their ends to said bars. End frames each are composed of angle

bars 17, 18 parallel with each other, vertically spaced apart and connected by vertically arranged metal strips 19 riveted at their ends to said bars. Sections of pipe 60 or tubing 20 are arranged vertically between corner portions of the base frame and end portions of the back and end frames (at the four corners of the completed structure) and bolts 21 are mounted through said pipes and 65 the overlapping end portions of frame bars and are secured by nuts 22 on their upper ends. The structure thus far described comprises a base, back and ends partially enclosing a rectangular parallelepipedon 70 adapted to give form to a collocation of objects contained therein.

A link 23 is pivoted at its lower end to the central portion of the bar 14 and a compressing lever 24 is formed with a goose-neck 25 75 at one end, which goose-neck is pivoted at its extremity to the upper end of said link. A handle 26 is formed on the opposite end portion of the compressing lever. A compressing yoke 27 is fixed to and depends from 80 the compressing lever 24 and is adapted to engage the collocation of articles in the frame at times. A hook 28 is pivoted at its lower end to the central portion of the bar 11 and is adapted to engage at times with 85 the compressing yoke 27 and hold the same in compressing position. A notch 29 may be formed in the central portion of the frame bar 15 and a hook 30 is pivoted at one end to said bar adjacent to said notch. 90

In practical use the parts of the frame are assembled as shown, varying in size and arrangement according to the size and shape of the bundle to be built up in it. When the device is to be used for baling shingles 95 the hook 28 is disengaged from the yoke 27 and the lever 24 and said yoke are moved away from the frame upwardly and rearwardly, articulating on the pivotal connection with the link 23. Then a tie or bond (common and well known in the manufacture of shingles) is arranged in the frame; one wooden cleat 31 of said tie lying on and transversely of the base frame, one metal strip 32 of said tie depending out of the way 105 at the outer end of said cleat and secured at one end thereto; the other metal strip 33 of said tie extending upwardly along or in a groove of the back frame and the remaining wooden cleat 34 fixed to and extending vertically from the upper end of the metal strip 33, the latter wooden cleat being confined 110

by the hook 30 and entering if desired the notch 29 in the bar 15. Then the shingles 35 are assorted and packed in laminated form with their butts engaging the strips 19 5 of the end frames and their thinner portions overlapping at the center of the package-containing space and overlying in sequence the cleat 31. When the desired number of shingles, usually twenty-five layers at each 10 end of the bundle, are accumulated as shown, the lever 24 and yoke 27 are moved into a position transversely of the frame, the yoke 27 being brought into contact with the uppermost layer of shingles 35. Then man- 15 ual pressure is applied through the handle 26 to cause the yoke 27 to compress the col- location of shingles to the desired degree, which done the hook 28 is applied to the yoke to hold it in compressing position. 20 Then the cleat 34 is released from the hook 30 and moved into recumbent position across the collection of shingles, the metal strip 33 being flexed to permit such movement of the cleat, and then the metal strip 32 is flexed 25 and brought alongside the center of the outer margin of the collection of shingles 35, is bent over and nailed to the outer end of the cleat 34. Then the hook 28 is released from the yoke 27 and moved into recumbent 30 position alongside of the bar 11, whereupon the yoke 27 and lever 24 are moved away from the bundle made as above described and said bundle is removed manually from the frame.

35 Much inconvenience and loss of material

is occasioned by the breaking of bales and opening of bundles of shingles and similar small objects and our device as above de- 40 scribed provides a convenient, economical and desirable means for re-baling or re-bun- dling such objects and thus conserving time in handling them and avoiding waste of material.

We claim as our invention—

1. A re-baling machine consisting of a 45 bottom, one side and parallel end portions suitably connected, a link rising from said bottom outside the side portion, a lever formed with a goose-neck at one end pivoted to said link, a yoke fixed to and extending 50 longitudinally of said lever and adapted to depend on the opposite side of the side portion from the link, and a hook adapted to connect the bottom and yoke detachably.

2. A re-baling machine consisting of a 55 bottom, one side and parallel end portions suitably connected, a link rising from said bottom outside the side portion, a lever formed with a goose-neck at one end pivoted to said link, a yoke fixed to said lever and 60 adapted to depend on the opposite side of the side portion from the link, and a hook adapted to connect the bottom and yoke detachably, and a pivoted hook adapted for 65 securing part of a bundle-retaining element to said side portion temporarily.

Signed by us at Mason City, Iowa, this
31st day of July, 1917.

JOHN NORRIS.
JESSE I. PEARSALL.
